JAMES SMITH LANIER, OF CHAMBERS COUNTY, ALABAMA.

QUILL-CLEANER ART.

1,190,918.

Specification of Letters Patent. Patented July 11, 1916.

Application filed April 10, 1913. Serial No. 760,259.

To all whom it may concern:

Be it known that I, JAMES SMITH LANIER, a citizen of the United States, residing in the county of Chambers and State of Alabama, have invented certain new and useful Improvements in the Quill-Cleaner Art; and I do hereby declare the following to be a full, clear, and exact description of the invention, such as will enable others skilled 10 in the art to which it appertains to make and use the same.

This invention relates to improvements in the art of quill cleaning, and particularly to means for removing waste yarn remaining 15 on quills, and also to the mode of removal thereof.

The object in view is the production of cheap and efficient means for quickly and automatically removing yarn from quills.

20 With this and further objects in view as will hereinafter in part be stated and in part become apparent, the invention comprises certain novel constructions, combination and arrangements of parts and certain 25 novel steps of a process, as will be herein-after specified and claimed.

In the accompanying drawing,—Figure 1 is a view partly in side elevation and partly in section of an apparatus demonstrating 30 the features of the present invention. Fig. 2 is a top plan view of the spiral housing with the chute and suction tube omitted. Figs. 3 and 4 are detail cross sectional views taken respectively on the planes indicated 35 by lines 3—3 and 4—4 of Fig. 1.

Referring to the drawings by numerals, 1 indicates a funnel supported in any suitable manner in position for discharging into a trough or guideway 2 which is inclined to 40 form a chute for quills or bobbins, a few of which are indicated at 4, 4. The chute 2 extends to the spiral housing 5 and communicates with the quill receiving slot 6 formed in the spiral portion of the housing 45 and leading downwardly about the housing. The slot 6 terminates in communication with a discharge chute 7 through which the quills 4 are adapted to be directed and to be allowed to drop therefrom into any suitable 50 receptacle disposed beneath the chute 7. The housing 5 is hollow throughout its length and at its lower end contracts abruptly, somewhat funnel-like, and discharges into a suction pipe 8 which extends to a 55 suction device or blower 9 of any ordinary or well known type.

In the length of the tube 8 is arranged the apparatus for preventing waste yarn drawn from the quills from clogging the blower 9, or otherwise interfering with the operation 60 of the parts. This apparatus consists of a transversely disposed chamber 10 interposed in the length of pipe 8 and having locks 11 and 12 at its upper and lower portions through which passes the endless cable 13 65 provided with brushes 14 adapted to sweep across the protecting screen 15 stretched across the intake portion of the tube 8. The cable 13 may be in the form of a sprocket chain or other suitable carrier sustained and 70 driven by shaft-carried sprockets or pulleys and supplied with power from any appropriate source not illustrated. Each lock 11, 12 is of the usual air lock type, such as are 75 commonly employed in caisson constructions, the lock 11 being provided with spring-closed, inwardly opening doors 16, 16, and the lock 12 being provided with spring-closed outwardly opening doors 17, 17, each of the doors 16 and 17 being apertured and 80 slotted for accommodating the cable 13.

In operation, the quills are dropped into the funnel 1, either manually or otherwise, so that their small or tapered ends extend downwardly, and are delivered from the 85 funnel by gravity in rapid succession end-wise into chute 2, down which they slide until they enter the slot 6. In practice, it is preferable to supply a sufficient quantity of quills to the funnel 1 to insure sufficiently rapid delivery to the chute 2 for 90 having the quills move along in edge contact with respect to their heads, the heads engaging the side walls of the chute while descending the chute and engaging the upper edge portions of the housing 5 while descending the same along the slot 6. The incline of such edges is sufficient to insure travel by gravity on the part of the several 95 quills throughout the length of the slot 6, so that they will be successively discharged from the chute 7. During such travel they are subjected to the sucking action of the 100 exhaust blower 9 and the remaining yarn on the respective quills will be rapidly drawn off of the same and down through the housing 5 into tube 8. It is obvious, of course, that a relatively large quantity, or 105 practically all, of the yarn thus drawn off will lodge on the screen 15 from which it 110 will be periodically removed by the brushes 14, the said brushes entering and leaving

the chamber 10 accompanied by a minimum admission of air by virtue of the employment of the locks 11 and 12.

I have demonstrated in practice the efficiency of the apparatus and the effectiveness of this mode or method of cleaning quills. I am, of course, aware of attempts to clean quills by mechanical strippers but of those with which I am familiar none of such have been successful in stripping all of the quills supplied to the machine, and it has, therefore, been found necessary in operating such mechanical strippers to assort the clean quills from the uncleaned ones and to place the latter again in the hopper of the machine for further cleaning. With the present apparatus and mode of quill cleaning this necessity is entirely obviated, as I find that usually during a very short portion 20 of the first part of the travel of the quills down the slot 6 the yarn is entirely removed. Even when the yarn is in most tangled condition it is found that the suction loosens and sufficiently disentangles the yarn to 25 start the free end portion and the continued suction rapidly unwinds the balance.

While I have described in detail a specific structure for carrying out the present improved mode of removing yarn from quills, 30 it is obvious that the mode may be carried out without limitation to apparatus and by apparatus of any of varying types. It will be further noted that the removal of the yarn under the sucking action of the fan or blower is incident to a resultant difference in atmospheric pressure whereby currents of air are caused to flow past the yarn, so that while it is proper to say that the 35 yarn is sucked off, it is also quite as accurate a statement to say that the yarn is blown off, the difference being that of the points of observation and represents no difference in fact. Thus regardless of the location of the fan or other apparatus which 40 produces the difference in atmospheric pressure, the resultant cleansing blast is the same and is effective incident to the flow of atmosphere or other fluid longitudinally of the respective quill or bobbin. It will be 45 observed that it is immaterial whether the blast be of air or other fluid, and, therefore, the term "air" as employed in the appended claims is to be interpreted in a broad sense inclusive of any possible substitute fluid. 50 The terms quill and bobbin are herein used as synonymous, and are employed to designate a yarn carrier of any kind where waste is left on the carrier and must be cleaned therefrom before the carrier can be reused, 55 or where it is desirable to recover the waste for the value of the yarn itself.

As will be obvious from Fig. 1, the action of the air blast or current passing the waste yarn of each bobbin or quill is to 60 segregate a strand and unwind the same so

that the waste yarn as discharged is in a condition incident to its removal from the bobbins in the form of segregated strands, which is a condition rendering the resultant waste product of yarn far superior for commercial purposes than is ordinary waste yarn removed by hand or otherwise from bobbins but left in the form of a bunch or condensed, tangled mass.

What I claim is:—

1. In a quill cleaner, the combination with a housing proportioned to receive a plurality of quills, and means for directing a cleansing blast through the housing in contact with all quills extending therein. 75
2. In the art of quill cleaning, causing traveling of a quill laterally into a line of blast with the quill disposed substantially longitudinally of the line of blast for subjecting waste yarn on the quill to the action 80 of the blast.
3. In the art of quill cleaning, moving a series of juxtaposed quills laterally into a line of blast and maintaining said quills positioned longitudinally of the line of blast 85 while subjecting waste yarn thereon to the action of the blast.
4. In the art of quill cleaning, subjecting waste yarn on a quill to a cleansing blast adapted to remove yarn from the quill, and causing the quill to travel laterally while 90 yarn on the quill is subjected to the blast.
5. In a quill cleaner, the combination of means for creating a cleansing blast, and means for directing a quill laterally into the 95 blast with the quill disposed longitudinally of the blast.
6. In a quill cleaner, the combination of means for creating a cleansing blast, and means for directing a plurality of juxtaposed quills laterally into the blast while the quills are sustained substantially longitudinally of the blast. 105
7. In a quill cleaner, pneumatic suction means, and means for placing a quill in the path of the suction for removing waste yarn from the quill. 110
8. In a quill cleaner, the combination of pneumatic suction means, and means for directing a quill along a path while subjected to the suction means. 115
9. In a quill cleaner, the combination of means for creating a cleansing blast and means for directing a quill into the blast for removing waste yarn therefrom. 120
10. In a quill cleaner, the combination of means for creating a cleansing blast and means for directing a quill into the blast with the quill disposed substantially longitudinally with respect to the blast for causing the blast to act directly on the quill externally thereof for removing waste yarn 125 therefrom.
11. In a quill cleaner, the combination of means for creating a cleansing blast and 130

means for directing a quill through the blast for causing the blast to remove the waste yarn from the quill.

12. In a quill cleaner, the combination of 5 means for directing a cleansing blast in contact with waste yarn on a quill, and means for causing the quill to move relative to the blast.

13. In a quill cleaner, the combination of 10 means for directing a cleansing blast in contact with waste yarn on a quill, and means for causing relative movement of the quill and blast with respect to each other.

14. In a quill cleaner, the combination of 15 pneumatic suction means, and means for moving a quill through the line of suction for removing waste yarn from the quill.

15. In a quill cleaner, the combination of 20 pneumatic suction means, and means for directing a quill through the line of suction with the quill disposed alined with such line of suction for removing waste yarn from the quill.

16. In a quill cleaner, the combination of 25 a slotted housing, and means for creating a partial vacuum in the housing, the slot of the housing being adapted to laterally admit quills for removing waste yarn therefrom.

17. In a quill cleaner, the combination of 30 a slotted housing, and means for creating a partial vacuum in the housing, the slot being adapted to receive the shank of a quill while the head of the quill is supported by the material of the housing.

18. In a quill cleaner, the combination of 35 a suction device, means for presenting a quill to the action of the suction device for

removing waste yarn from the quill, and means for moving the yarn sucked from the quill out of the path of the suction.

19. In a quill cleaner, the combination of 40 a suction device, means for presenting a quill to the action of the suction device for removing waste yarn from the quill, a screen disposed between the suction device and the quill, and means for cleaning the screen.

20. In a quill cleaner, the combination of 45 means for removing waste yarn from a quill by the action of an air blast operating directly on the yarn being removed, and means 50 for automatically feeding quills into the line of the blast.

21. In a quill cleaner, the combination of 55 pneumatic means for removing waste yarn from a quill, and means for automatically feeding a quill to said yarn removing means.

22. In a quill cleaner, the combination of 60 pneumatic means for cleaning waste yarn from quills, and means for automatically feeding quills successively to the yarn cleaning means.

23. In a quill cleaner, the combination of 65 means for producing a cleansing blast, and automatic means for feeding and positioning a quill longitudinally with respect to the blast for enabling the blast to remove waste yarn from the quill.

In testimony whereof I affix my signature in presence of two witnesses.

JAMES SMITH LANIER.
